United States Patent Office

Des. 203,425
Patented Jan. 4, 1966

203,425

AIRCRAFT

Lawrence Bernard Rellis, San Diego, Calif.
(734 NW. 80th St., Apt. 16, Miami, Fla. 33150)

Filed Nov. 4, 1964, Ser. No. 82,463

Term of patent 14 years

(Cl. D71—1)

E-7-4

E-7-5

FIG. 6

FIG. 7

FIG. 1 is a perspective view of the aircraft in flight with the exhaust directors of the rear engines in the extended position and the side engines rotated to the horizontal.

FIG. 2 is a top plan view thereof;

FIG. 3 is a side elevational view of the aircraft in the take-off position.

FIG. 4 is a bottom plan view thereof;

FIG. 5 is a side elevational view of the opposite side;

FIG. 6 is a front elevational view thereof; and

FIG. 7 is a rear elevational view.

I claim:

The ornamental design for an aircraft, as shown and described.
